UNITED STATES PATENT OFFICE.

JOHN F. SIMONS, OF PHILADELPHIA, PENNSYLVANIA, ASSIGNOR TO HIMSELF AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY.

DESIGN FOR A SHOW OR DISPLAY CARD.

SPECIFICATION forming part of Design No. 27,521, dated August 17, 1897.

Application filed April 24, 1897. Serial No. 633,801. Term of patent 14 years.

To all whom it may concern:

Be it known that I, JOHN F. SIMONS, of Philadelphia, county of Philadelphia, and State of Pennsylvania, have invented a new and original Design for Show or Display Cards, of which the following is a specification.

My design relates to designs for show or display cards, and is fully illustrated in the accompanying drawings, in which—

10 Figure 1 shows an elevation of a show-card embodying my design, and Fig. 2 shows a cross-sectional view of the same on the line xx .

The design consists of a conventional thimble shape having portions of its surface cut 15 out, as at a , to form tongues b . I have shown the upper portion or crown B with a series of $\wedge$ -shaped cuts a , arranged in rows and forming series of rows of tongues b , each of which is inclosed in an encircling line c . The crown

thus presents the appearance of a series of 20 rows of ovals each containing a $\wedge$ cut or opening a .

The essential feature of the design is a conventional thimble shape having a portion of its surface formed with a series of openings, 25 forming a series of tongues b .

Having now described my invention, what I claim as new, and desire to secure by Letters Patent, is as follows:

The design for a show or display card substantially as described and shown.

In testimony of which invention I hereunto set my hand.

JOHN F. SIMONS.
